METHOD OF ELECTRICALLY CONNECTING A WIRE TO A CONDUCTIVE BODY
Otto Uebelmann, 5 Frankfurterstrasse, Wahn, Germany
Filed Feb. 20, 1957, Ser. No. 643,909
1 Claim. (Cl. 29—155.55)

The instant invention relates generally to electrical conducting elements, and more particularly, to a method and means for securing electrical conducting wires to an electrical connecting element.

Connecting elements which are employed in the transmission of electrical energy must provide a relatively strong mechanical bond between the current conducting wires, and the connecting elements as well as a suitable electrically conducting junction. The desired result may be achieved by pressing or soldering caps or collars on the ends of the connecting elements to fasten the conducting wires thereto or by upsetting the current conducting wires within the cylindrical sockets formed in the ends of the conducting elements.

It may be readily apparent that the use of caps, and/or collars necessitates a considerable consumption of material and presents interelement capacities to the arrangement which pose a rather serious problem when dealing with the transmission of high frequency electrical energy.

The present invention is directed principally to an upsetting process of connecting a current carrying wire and a connecting element wherein the free shank of the end of the current carrying wire is bent through substantially 180° and disposed within a socket formed in the connecting element and subsequent to the introduction therein is upset by means such as a punch to thereby achieve the desired junction.

The invention will be clearly understood by reading the following detailed description in conjunction with the drawings, in which:

FIGURE 1 is a fragmentary sectional view of a connector specifically illustrating the disposition of the current carrying wire in the socket of the connector,

FIGURE 2 is a view similar to the view of FIGURE 2 showing the current carrying wire after it has been pressed into place, and

FIGURE 3 is a fragmentary sectional view of an alternate form of the invention.

A ceramic resistant body 1 is provided with elongate sockets 4 formed at each end thereof.

A resistance layer 2 is formed to completely surround or envelop the body 1 and consists of an electrically conductive material, such as for example, lustrous carbon. Manifestly, this layer is applied to the inner surfaces of the sockets 4 as well as the outer surface of the body 1. The coating 2 may be applied to the body 1 by painting, dipping, spraying or the like. Frequently, the use of such electrical connecting elements in the transmission of electrical energy over long distances during which time the elements are exposed to a great deal of moisture and other adverse conditions may make it highly desirable to envelop the elements with appropriate protective coverings. It has proved advantageous in certain applications to provide a plurality of thin protective layers of different properties thereby forming in effect a laminated coating of protective material rather than a single outer layer. In such instances, the coating may be comprised of a thermoplastic or a hardening synthetic resin in addition to the lustrous carbon material. It has been found that in applications wherein the elements are to be exposed to severe use, the outer protective layer may be satisfactorily formed of material having substantial resistance to puncture, such as for example polyvinyl chlo-

2

ride, polyvinyl carbazole, polyamide, polyethylene or rubber hydrochloride.

It will be noted that the ceramic body 1 has bosses 3 formed integral therewith to effectively protect the material 2 from injury in the region of the ends or terminal portions of the body 1.

The elongate socket 4 formed in the ends of the body 1 is adapted to receive the current conducting wires 5 as illustrated in the drawing. The sockets 4 are generally of a size sufficient to receive the conducting wire 5 when the terminal portions thereof have been bent upon itself to conform to the shape of a U. With the U-shaped arrangement of the wires 5, a good mechanical and electrical connection may be readily achieved in accordance with the teachings of the instant invention by tamping, forcing, or upsetting the free terminal end of the wires 5 after disposition within their respective sockets 4. The tamping operation necessarily deforms the metal of the wires 5 and causes it to flow against the exposed faces of the sockets 4. By reason of the friction thus produced between the wires 5 and the body 1 of the connecting element, retraction of the wires is nearly impossible without fracturing the wire or breaking the ceramic body 1. With the U-shaped configuration of the conducting wire, any attempt to separate the wire from the ceramic body 1 will necessitate the unrolling of the wire in the socket 4 due to the fact the terminal portion of the wire has been spread out causing its free end to be in intimate contact with the surface of the interior of the sockets 4.

It will be readily apparent that good electrical contact is maintained between the conducting wire 5 and the conducting layer 2 which has been formed on the interior surface of the sockets 4 of the body 1. In certain applications, improved electrical contact may be achieved, if desired, by filling any hollow spaces within the sockets 4 by a substance such as a graphite solution or a conducting cement.

The alternate form of the invention shown in FIGURE 3 comprises a ceramic body 11 having a socket 12 at one end, the sides of the socket having a series of grooves 13. Disposed within the socket is the end portion of the current carrying wire 14, the L-shaped end 15 being upset to fill the cavity similar to that shown in FIGURE 2. A hardening cement, solder, or the like indicated at 16, affords additional securing means for retaining the wire in the body. Covering the body 11 is a protective coating 17 of lacquer and upon the coating 17 is a shrunk-on layer 18 of great resistance to puncture. Layer 18 may be of polyvinyl chloride, a polyvinyl carbazole, a polyamide, polyethylene or a rubber hydrochloride. The hardening cement, solder, or the like indicated at 16 completely fills all the hollow spaces or voids in the elongate socket 12 in order to further increase the mechanical and electrical bond between the connecting element and the current carrying wire.

This application is a continuation in part application of an earlier filed copending application Serial Number 326,444, filed December 17, 1952, now abandoned.

Having fully explained the invention in accordance with the patent statutes by means of some embodiments it is clear that the invention is not to be restricted to these embodiments and it is desired to include within the invention all embodiments falling within the scope of the appended claim.

65 What is claimed is:

A method of securing an electrically conducting wire to a substantially brittle electrically conductive body comprising the steps: bending an end portion of an initially substantially straight electrically conductive malleable metal wire through approximately 180° to form a closed bend including a free shank extending substantially parallel and contiguous to the unbent portion of the wire,

inserting said closed bend into a socket in the body slightly larger in cross section than said closed bend and shaped to accept said bend, and thereafter applying a sufficient degree of force axially against the end of said free shank to upset said shank into tight engagement with the interior surface of said socket.
